Joseph L. Levy

UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

GARMENT-SHIELD.

1,363,727.

Specification of Letters Patent. Patented Dec. 28, 1920.

Application filed June 4, 1920. Serial No. 386,562.

To all whom it may concern:

Be it known that I, VICTOR GUINZBURG, a citizen of the United States, and a resident of the city, county, and State of New

5 York, have invented a certain new and useful Improvement in Garment-Shields, of which the following is a specification.

The object of this invention is to provide a garment shield which will be light in construction; which can be economically made, and which may be worn with comfort.

A further object of this invention is to provide a garment shield of the character above mentioned which will be held in place 15 on the wearer without the necessity for sewing the same in position in a garment and without the use of pins or other objectionable fastening devices; and which when placed in position, will remain so under all conditions of wear.

With these objects and other objects which may hereinafter appear in view, I have devised the particular arrangement of parts hereinafter set forth and more particularly pointed out in the claims appended hereto.

In the accompanying drawing, Figure 1 is a front elevation of a garment shield, provided with my invention;

30 Fig. 2 is a rear elevation of the same, and Fig. 3 is a transverse sectional view of the connecting strip between the shields.

Throughout the various views of the drawings similar reference characters designate 35 similar parts.

In the preferred embodiment of my invention, as disclosed in the accompanying drawing, it will be seen that I have provided a pair of arm shields, each of which 40 is composed of a body flap 1 and an arm flap 2. At the juncture of the two flaps 1 and 2 I provide a cord 3 which is preferably in the nature of elastic material and which passes over the shoulder of the wearer to 45 hold the shields close to the arm pit.

The arm flap 2 is provided with a transversely extending elastic cord 4 which extends about the arm of the wearer and causes the flap to be held closely thereto. 50 Secured to the inner face of each of the body flaps 1 is a flap 5 which is preferably, for convenience and comfort, made of a netted or open mesh material as shown at 6 and extending from the end of each of these 55 flaps 5 is a tying tape or ribbon 7. It will

be understood that the flaps 5 extend at the front of the wearer and to secure the device in place, the tapes or ribbons 7 are tied or otherwise secured together.

Connecting the shields is a strip of elastic 60 fabric 8 which passes about the back of the wearer. This strip is connected at its ends to the inner face of the body flap 1 by the stitches 9 as shown in Fig. 2.

The strip 8 is preferably composed of a 65 section of inelastic fabric which is gathered or Shirred to produce a number of folds 12. Secured to the inner face of said inelastic strip are a number of spaced-apart strips of a flat unshirred elastic material 13. These 70 strips are preferably in the nature of narrow elastic webbing.

It will be noted that the inelastic strip of fabric 10 is provided with hems 14 at its longitudinal edges which hems are secured 75 by the lines of stitching 15. It will be also noted that these lines of hem-stitching 15 secure the edge-strips of elastic material 13 to the inelastic material. The central strip of elastic material 13 is held in place by a 80 longitudinally extending line of stitching 16.

It will be seen that the entire strip 8, constructed as above set forth, is expansible longitudinally within the limits of the folds 85 or shirring of the inelastic material 10. It will also be noted that intermediate of the elastic strips 13, the inelastic material 10 possesses a fullness which permits slight lateral expansion and which tends to enhance the appearance of the strip 8, likewise permitting the strip to conform to the body under all conditions of wear.

From the foregoing it will be obvious that my invention is not to be restricted to the 95 embodiment shown but is broad enough to cover all structures coming within the scope of the annexed claims.

Having described my invention, what I claim is—

1. An article of the class described comprising a pair of dress shields, an expansible strip connecting the same, said strip comprising an elongated section of shirred inelastic material, having inturned or hemmed 105 edges, stitching securing said hems in position and likewise securing strips of flat unshirred elastic material to the face of the shirred strip.

2. An article of the class described com-

100

110

prising a pair of dress shields, an expandible strip connecting the same, said strip comprising a section of shirred material having its edges hemmed, a line of stitching extending along each of said edges to produce the hems, a strip of flat elastic material secured adjacent to the edges of the shirred

strip by said stitching and a strip of flat elastic material secured to the face of the shirred strip intermediate of the elastic edge strips.

Signed at the city, county and State of New York this 2nd day of June, 1920.

VICTOR GUINZBURG.
